(57) **CLAIM**

We claim the ornamental design for a model vehicle assembly, as shown and described.

DESCRIPTION

FIG. 1 is an upper, left, front perspective view of a model vehicle assembly;

FIG. 2 is front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a lower, right, rear perspective view thereof.

In the drawings, the broken line showing of features of a model vehicle assembly illustrate portions of the model vehicle assembly that form no part of the claimed design.
